UNITED STATES PATENT OFFICE.

CHARLES BABSON, OF GLOUCESTER, MASSACHUSETTS.

NECKWEAR.

SPECIFICATION forming part of Letters Patent No. 754,188, dated March 8, 1904.

Application filed October 3, 1903. Serial No. 175,574. (No model.)

To all whom it may concern:

Be it known that I, CHARLES BABSON, a citizen of the United States, and a resident of Gloucester, in the county of Essex and State of Massachusetts, have invented a new and useful Improvement in Neckwear, of which the following is a full, clear, and exact description.

My invention relates particularly to the construction of the tip for the neckbands of made-up scarfs, but is applicable to analogous articles.

The object of the invention is to provide a tip for the neckbands of neckties which will automatically lock itself in adjusted position, dispensing entirely with the ordinary retaining-pin, and to so construct such a tip that it will be not only simple, durable, and economic, but which may be threaded through the tie in the customary manner, expanding to retain its position the moment it is released in adjustment.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a rear elevation of a made-up scarf, showing the application of the improved tip, a portion of the neckband receiving the tip being broken away. Fig. 2 is a longitudinal section taken practically on the line 2-2 of Fig. 1. Fig. 3 is a detail perspective view of the tip; and Fig. 4 is a side view of the tip, illustrating a slight departure in its construction.

A represents the head of a made-up scarf; B, the skirts thereof; C, the neckband, and D the improved tip, which is located within the neckband at its free end.

The head A of the scarf is provided with the customary passage 10, through which the free end of the neckband is passed; but, as has been stated, a retaining-pin is not used. Preferably at the outlet end of the passage 10 a wall 11 is formed of elastic or of metal, so as to offer more or less resistance to the free end

of the neckband when carried through the said passage 10.

The tip D consists of two opposing members 12 and 13, preferably made of a spring material, such as light steel. These body members 12 and 13 are secured together at their ends by rivets 14 and 15 or their equivalents. The body members 12 and 13 are adapted to be forced in opposite directions, as is shown in Figs. 3 and 4, and they may be normally curved or bowed in opposite directions; but the said body members 12 and 13 are held separated between their ends by one or more interposed springs 16, preferably spiral or helical in shape.

After the tip has been placed in the free end of the neckband a cap 17 is preferably exteriorly located and secured to the free extremity of the neckband, as is illustrated in Figs. 1 and 2.

In operation when the free end of the neckband carrying the improved tip is passed through the passage 10 the body members 12 and 13 are compressed more or less, placing the spring or springs 16 under tension, and after the tipped end of the neckband has been properly adjusted in the head A of the tie and the free end of the neckband is released the springs 16 act to force the body members 12 and 13 outward in opposite directions, thus forming a barrier which prevents the neckband from being disengaged at its free end from the head of the scarf until purposely removed.

The resisting section 11 of the passage 10 of the head A serves to retard the free end of the neckband if it has a tendency to work out from the head of the tie.

I desire it to be understood that I do not confine myself to any form of spring for expanding the tip.

Having thus described my invention, I claim as new and desire to secure by Letters Patent—

1. A tip for the neckband of neckties and analogous articles, consisting of flat elongated opposing members bowed outwardly from each other at their central portion and having their end portions connected together in flat engagement with each other.

2. A tip for the neckband of neckties and

analogous articles, consisting of opposing members and an interposed spring, as described.

3. A tip for the neckband of neckties and analogous articles, comprising opposing members connected at their ends, and a spring located between the members, adapted to normally spread them apart, as described.

4. A tip for the neckband of neckties and analogous articles, consisting of two oppositely-curved spring body members connected at their ends, and a tension-spring located between the ends of the body members, acting to normally force them apart, as set forth.

15 5. The combination with the head of a neck-

tie and attached neckband, the head being provided with a passage for the free end of the neckband, which passage has a section of resisting material, of a tip for the neckband, comprising opposing body members connected at their ends, and an interposed spring which normally supports the body members between their ends, as described.

In testimony whereof I have signed my name to this specification in the presence of two subscribing witnesses.

CHARLES BABSON.
